UNITED STATES PATENT OFFICE

160,433

VASE OR SIMILAR ARTICLE

Russell L. Rust, San Marino, Calif.

Application March 23, 1949, Serial No. 1,577

Term of patent 7 years

(Cl. D29—28)

To all whom it may concern:

Be it known that I, Russell L. Rust, a citizen of the United States, residing at San Marino, in the county of Los Angeles and State of California, have invented a new, original, and ornamental Design for a Vase or Similar Article of which the following is a specification, reference being had to the accompanying drawing forming, a part thereof.

I claim:

The ornamental design for a vase or similar article, substantially as shown.

RUSSELL L. RUST,
